SEWING MACHINE

John P. Weis, Nyack, N. Y., and Frederick F. Zeier, Bridgeport, Conn., assignors to Willcox & Gibbs Sewing Machine Company, New York, N. Y., a corporation of New York

Original application October 27, 1934, Serial No. 750,259. Divided and this application January 20, 1938, Serial No. 185,886

12 Claims. (Cl. 112—260)

The present invention relates to improvements in sewing machines, and particularly to improvements in the lower or work supporting arm construction and the associated structures therein and thereon. This application is a division of the co-pending application Serial No. 750,259, filed October 27, 1934, and now Patent No. 2,145,824, granted January 31, 1939.

It is a primary object of the present invention to provide a single sewing machine which may be made into and used equally well as a so-called flat bed or feed across the arm type of sewing machine and also a cylindrical or feed around the arm type for hemming bloomers, step-ins, trouser and overall legs, and the like.

Complementary aims of this object are to provide a machine that has free access to the stitching instrumentalities for convenient threading, cleaning, and adjusting, whereby free space is provided for a large variety of attachments, readily adapting the machine to a wide variety of stitching requirements.

In the accomplishment of this object and the various aims, a machine has been developed with numerous advantageous features of construction, among which may be noted: an improved lower or work supporting arm, which is sturdy and easily cleaned, including novel cloth plates and throat plates supported thereby, and which may be removed or changed one without the other; the cloth plates being of various sizes all supportable on the one lower arm to change the machine from a flat bed type to a cylindrical or feed around the arm type, the arm having special supports so that it may be located and held with the head end projecting from a table to permit feeding around the arm.

Further, this improved lower arm supports interchangeable throat plates, provided with an underlying adaptor, making possible the use of thin throat plates with thick cloth plates, independent removal of the plates, ample support for the thin throat plate while providing plenty of clearance for underlying loopers.

It is a further object of the present invention to provide an improved support whereby loop spreaders for operating on the looper threads may be interchanged without the necessity of disassembling the cloth plate from the arm. Thus, when changing from a single needle to a double or triple needle set-up, and when the throat plate is necessarily changed, the loop spreader of the present invention may be removed therewith and a double or triple loop

spreader may be added to the arm again with the changed throat plate.

Another feature of this improved lower arm is that, despite its interchangeable characteristics, it may be made as an integral part of the main frame, and despite its small size it may be made very sturdy to withstand the stress and strain of operating multiple needles and loopers for gang stitching at high speed through thick, thin, and needle resistant materials. Further, this novel work supporting arm provides for the free passage of lint, grit, waste materials, and various substances that come from sewing, to prevent an accumulation of such materials interfering with the regular operation of the machine, means being provided so that such foreign matter may pass through or out of the way of working parts to avoid clogging.

Other features and advantages will appear hereinafter.

In the drawings:

Figure 1 is a sectional view taken longitudinally through the complete machine of the present invention.

Fig. 2 is a transverse sectional view taken through the working or head end of the machine, taken on line 2—2 of Fig. 1.

Fig. 3 is a transverse sectional view through the trunk end of the machine, taken on line 3—3 in Fig. 1.

Fig. 4 is a horizontal sectional view, taken on line 4—4 in Fig. 1.

Fig. 5 is a top sectional view taken on line 5—5 in Fig. 1 and shows the cloth plate removed.

Fig. 6 is a sectional view similar to Fig. 2 but shows the longitudinal type looper and the wide cloth plate in place on the lower arm, forming the flat bed or feed across the arm type of machine.

Fig. 7 is a view similar to Fig. 6 but shows a modified form of structure for the outer end of the lower arm and shows the narrow cloth plate in place, viz. the cylindrical or feed around the arm type of machine.

Fig. 8 is a detail top view of the loop spreader slide.

Fig. 8A is a front view of a modified form of slide similar to that shown in Fig. 8.

Fig. 9 is a fragmentary top view of the needle guard.

Fig. 10 is a sectional view through the front and outer end of the lower arm, showing the front of the needle guard and the loop spreader.

Fig. 11 is a top view of the large cloth plate on a reduced scale.

Fig. 12 is a top view of the small cloth plate, shown in Fig. 7, and shown by dash lines in Fig. 4.

Fig. 13 is a top view of the adaptor plate.

Fig. 14 is a top view of one form of throat plate.

Fig. 15 is a top plan view of the loop spreader operating connection.

The present invention is not limited to the details of construction and arrangement of parts illustrated in the accompanying drawings since the principles of the invention are capable of other embodiments, and the phraseology employed is for the purpose of description and not for limitation.

Frame and trunk

Referring now in detail to the drawings, the sewing machine of the present invention includes a frame 12 comprising a hollow trunk 13 for supporting a main driving mechanism 14, with a preferably hollow and integral upper arm 15 for supporting a needle operating mechanism 16, and a preferably integral lower arm 17 for supporting looper and feeding mechanisms 18 and 19 respectively and for forming a work support 20. In general it has a smooth outer finish for appearance, ease in cleaning, and elimination of all outward obstructions which would interfere with handling the work.

The hollowed trunk 13 comprises a front wall 21, rear wall 22 and side walls 23 and 24, the latter having large side openings 25 and 26 respectively to accommodate and support the main driving mechanism 14. Further, the trunk 13 is provided with a top opening 27 and a bottom opening 28 large enough to pass various operating parts and to receive the hands of a person making the original assembly or making subsequent repairs and adjustments. A cover plate 29 and a bottom plate 30 are provided for the top and bottom openings 27 and 28 respectively, and are held in place with screws. End caps 31 and 32 are similarly held against the side walls 23 and 24 respectively by screws 31' and 32' to make a complete oil tight closure for the main operating parts.

These openings and caps permit bench assembly of the operating parts contained in the trunk of the machine and facilitate assembly thereof by making it possible to pass the main driving mechanism 14 or large sub-units thereof through the various openings. When the caps are secured thereto an effective seal is provided which prevents leakage of oil while the machine is in operation.

The upper arm 15 is preferably made with a substantially hollow chamber 33 and may be of a substantially rectangular and tapering cross section, with a transverse web 34 at the trunk end, and a similar transverse web 35 near a head 36 at the end of the arm, to support a main rock shaft 37 of the needle operating mechanism 16. The head is provided with suitable bearings 38 and 39 for a needle bar 40 and a presser bar 41, see Figs. 1 and 2, and is provided with a large opening 42 to facilitate adjustments and repairs to the parts therein. This opening is normally closed with a cover plate 43, held in place by screws 43', to cover up the working mechanism and to prevent adverse escape of oil.

Lower arm (brief description)

Although the lower arm 17 and the associated

parts form the main subject matter of the present application, but brief reference is made thereto at this point in order to clearly describe the manner in which it supports the looper mechanism 18 and the feeding mechanism 19. After the latter are described in detail the important features of the lower arm will be described more fully.

Basically the lower arm 17 comprises a front wall 44 and a rear wall 45 extending horizontally from the trunk 13 in a direction parallel to and underlying the upper arm 15. Although these arms may be secured to the trunk by screws or other well known fastening means they are for rigidity and economy preferably made integral with the trunk. In order to provide suitable bearings for important operating parts an end wall 46 is provided at the outer extremities of the front and rear walls 44 and 45 respectively and a shorter transverse web 47 is provided intermediate the end wall 46 and the sides of the walls 44, 45 and 23.

Main driving mechanism

The main driving mechanism 14 is described herein, first in connection with the transverse looper 62, illustrated in Figs. 1 through 5, and then briefly in connection with a longitudinal looper 134 shown in Figs. 6 and 7. The novel lower arm structure of the present application is also equally applicable for use with the universal type loopers fully illustrated and described in the application Serial No. 745,343, filed September 24, 1934 by John P. Weis and Frederick F. Zeier and now Patent No. 2,145,822, granted January 31, 1939. It comprises a main drive shaft 64 with cranks A, B, C, D, and E, accommodating main driving connections including crank arms 65, 66, 67, 68 and 69 respectively provided with ball and socket connections 70, 71, 72, 73 and 74 between driving plates 75 (see Fig. 1).

Each of the crank arms 65 through 69 is preferably provided with a ball and socket and like connections 76, 77, 78, 79 and 80 respectively for connection to an arm 81, bell crank 82, arms 83 and 84, and link 85 at their ends opposite the main drive shaft, for operating the needle operating and other mechanism all in a manner about to be described.

This centrally located main drive shaft 64 supported in bearings 86 and 87 brings the handwheel 89 into a location where it may be very conveniently grasped without awkward twisting of the arm, and without danger of skinning knuckles as occurs sometimes when the handwheel is close to the base of the machine. Further, it makes possible the use of short crank arms to the various mechanisms, thereby overcoming vibration and inertia of moving parts to a very marked extent. This latter factor is enhanced by having the main drive shaft parallel the rocking and reciprocating rods of the various associated mechanisms.

Needle operating mechanism

The needle driving mechanism 16 comprises the rocker rod 37 journaled in bearings 34' and 35' in the walls 34 and 35 respectively with an arm 81 secured to the trunk end thereof by a yoke 81' and having a bearing stud 90 at its outer end connecting with the ball socket 76 at the upper end of the crank arm 65. At the head end 36 of the arm 15 the rocker rod 37 is provided with a needle driving arm 91 adjustably secured thereto by two screws 91' for adjusting the retracted and projected position of a needle 93 relative to

the head 36 and the looper 62. This arm is connected to the hollow needle bar 40 through a double link 92 and link pin connections 92' (see Fig. 2). At its lower end the needle bar is 5 adapted to interchangeably receive various types of needles 93 in the conventional manner. One vertical reciprocation of the needle downward and upward is accomplished by the crank arm 65 each time the crank "A" on the main drive 10 shaft 64 is given a complete revolution.

Transverse looper

As shown in Figs. 1 through 5 particularly, the looper mechanism 18 includes a looper carrier 97 having a pivot connection 98 projecting from a collar 99. The looper carrier 97 is provided with a hole 100 adapted to receive a looper 62 having a thread carrying and loop engaging blade 101, held therein by a screw 102. Various types and shapes of loopers, depending upon the stitch formation desired, may be supported in the one carrier in this manner.

The collar 99 is rotatable on an upper rod 103, the latter being supported for reciprocatory 25 movement in bearings 104 in the trunk 13 and in the lower arm 17. The collar is held against axial movement thereon by thrust collars 105 after the looper 62 is properly located with respect to the needle 93. Spacing between the collars 105 is just enough to prevent adverse axial movement of the collar 99 on the upper rod 103, yet sufficient to permit a free rotating or rocking movement on the rod.

In order to move the looper 62 relative to the 35 needle in an elliptical path in the usual and well known manner to form a Federal Standard Stitch Style 401, the lower end of the looper carrier 97 is provided with a double pivot connection 106 to a lower rod 107 journaled in bearings 108 and the upper and lower rods 103 and 107 respectively provided with driving connections 109 and 110, see Figs. 1 through 5. The connection 109 for the upper rod 103 includes the crank arm 66 having the ball and socket connection 71 45 with the crank B on the main drive shaft 64 and with a ball and socket connection 77 to the bell crank 82 pivotally mounted on a cross shaft 111, the bell crank having a ball and socket connection 112. The main connection 110 for the lower 50 rocker rod 107 includes the crank arm 67 having the ball and socket connection 72 with the crank C on the main drive shaft 64 and having a ball and socket connection 78 to the front end of the arm 83 secured to the lower rocker rod.

Reciprocation of the upper rod 103 moves the 55 looper 62 from the solid line to the dot-and-dash line position and vice versa, shown in Fig. 1, and rocking movement of the lower rod 107 moves the looper from solid line to the dot-and-dash line position shown in Fig. 2, all in timed relation with reciprocation of the needle 93. The lower rocker rod 107, is held in desired position lengthwise of the bed by collars 108' engaging bearings 108. The upper rod 103, however, is not held 60 against endwise movement since it must be reciprocated in the bearings 104 in order to impart rocking movement to the looper carrier 97.

Feeding mechanism

The feeding mechanism 19 for moving materials through the machine comprises a feed 70 rocker rod 114 and a feed lifter rod 115 mounted in suitable bearings in the lower arm 17 and the trunk 13. This mechanism is best seen in Figs. 2 and 5 and in a slightly modified form in

Figs. 6 and 7. It comprises a feed dog 63 secured to a feed dog carrier 116 as by screws 117, and this carrier in turn is connected to an arm 118 adjustably clamped to the rock shaft 114 by a split clamp construction 119 through a spring 120 5 under screws 121 and at its other end has a connection through a flat spring 122 and coil spring 123 to an arm 124 having a yoke connection 125 to the feed lift rod 115.

The feed dog 63 passes through suitable apertures 49' in the throat plate 49 in the usual manner and is given a four-motion movement through timed rocking of the feed rock rod 114 and feed lift rod 115. Any suitable feed dog, depending upon material and stitch requirements, 15 may be secured to the carrier as by the screws 117, and any suitable mating throat plate may be provided. Cooperating with the feed dog 63 is a presser foot 127 carried by the presser bar 41, which is tubular and operated in the bushing 20 39 in the head 36 in the well known manner.

A connection 128, see Figs. 1, 3, 4, 5, including an arm 84 connected by a yoke 130 between the feed lift rod 115 and a ball and socket connection 79 to the lower end of the crank arm 68 is provided to rock the feed lift rod. Thus, each time the crank D is given one complete turn, the lower end of the arm 124, see Figs. 2 and 5 through 7, is oscillated a predetermined extent and the spring 122 at the end thereof lifts the feed dog 30 63 from a position below the throat plate 49 to a position level with the top thereof or slightly above it to grip the materials between it and the presser foot 127.

Similar rocking movement is imparted to the 35 rod 114 through a connection 132 to the link 85 and crank arm 69 (see Fig. 3), to impart material carrying movement to the feed dog 63. The extent of feeding travel is regulated by an adjusting mechanism 133.

40

Longitudinal looper

The feeding mechanism just described and the main driving mechanism 14 described hereinbefore are equally applicable with longitudinal looper 134, best seen in Figs. 6 and 7, having its main travel longitudinally or parallel with the line of feed. With this type of looper a carrier 97' is rigidly secured to the upper rod 103 by a yoke 99' and is given a four-motion operation 45 by reciprocating the rod 103 as with the crank arm 66 and bell crank 82 and is rocked as by having the crank arm 67 and associated parts connected to the upper rod 103 rather than to the lower rod, described more fully in the co-pending 50 application Serial No. 745,343, filed September 24, 1934. This co-pending application also discloses and describes a universal looper mechanism in detail. These three forms of looper, viz., transverse, longitudinal, and universal are equally applicable for use in the novel lower arm forming 55 the main subject matter of this application.

Lower arm (detailed description)

The lower arm 17 is preferably made integral 65 with the frame 12, with a front wall 44 and a rear wall 45 extending horizontally from the trunk 13 in a direction parallel to and underlying the upper arm 15. In order to make these walls rigid or sturdy at the outer extremities, 70 and in order to provide suitable bearings for important operating parts, an end wall 46 is provided at their outer extremities and a shorter transverse web 47 is provided intermediate the end wall 46 and the sides of the walls 44, 45, and 75

23. Thus, the lower arm 17 provides a sturdy nonvibrating support for both the feed mechanism 19 and the looper mechanism 18, detailed description of which is given hereinbefore. Also, 5 the arm is provided with a foot 17' for supporting and securing the machine to a bench and for allowing the outer end thereof to be free and clear of the bench or table.

The lower arm 17 is arranged to provide a work 10 support 20 of a short height and width, and to provide a sturdy and quickly interchangeable support for a throat plate 49. Supports 50, 51, and 52, best seen in Fig. 5, are provided on the front wall 44 and associated rear lugs 53, 54, and 15 55, are provided on the rear wall 45 to form a support for the wide and large area cloth plate 56, best seen in Figs. 4, 6, and 11, which may be secured thereto by screws 57 entering tapped holes 57', or may likewise and interchangeably 20 support a narrow and small area cloth plate 58 as shown in Figs. 7, 12 and by dot-and-dash lines in Fig. 4.

These wide and narrow cloth plates 56 and 25 58 and the interchangeable characteristics thereof are a very important feature of the present invention. In most cases a machine of the "so-called" feed across the arm type with a wide cloth plate for long straight run sewing is preferred. However, for certain kinds of work, for example 30 the sewing of bloomers, stocking tops, trouser ends, etc., a so-called cylindrical or feed around the arm type of machine is required.

Ordinarily a manufacturer or user of sewing 35 machines must have separate machines for each type of sewing. So far as applicants are aware the present invention is the first to provide structure for changing from one to the other type of machine, which results in a considerable saving of investment in machinery and considerably reduces the amount of floor and bench space required.

The cloth plates 56 and 58 are normally made 40 of thick material for strength and rigidity and are provided with a depthwise cut-out or aperture 59, adapted to merely locate and not to support an adaptor 60 and the throat plate 49. As may best be seen in Figs. 1, 2, 3, 4, and 5, the lugs 50, 51, 53, and 54 are adapted to directly support the adaptor 60 and the throat plate 49, the latter being secured to the adaptor by screws 61 threaded into holes 61'. Interchangeable 45 throat plates may be provided with various cut-outs to accommodate various stitching combinations, different holes 93' to accommodate needle 50 gauges for light and heavy work, and various feed dogs. The main purpose of the adaptor 60 is to make possible the use of a thick cloth plate 56 with relatively thin throat plates 49, both resting upon the same bosses and more particularly to form a clearance for loopers 62, and feed dog 63, see Figs. 1, 2, and 5.

This adaptor 60 also forms a rigid support 55 for the throat plate to prevent deflection under heavy pressure from the needle when operating on heavy materials, and prevents deflection under heavy pressure of the presser foot. In addition, this arrangement of parts is such that the change-over from the wide cloth plate 56 to the narrow cloth plate 58, and in effect the change 60 from a flat bed to a cylindrical machine, may be effected without disturbing the throat plate which is desirable when there is a critical adjustment between the throat plate, feed dogs, and the needle guide. Also, it is possible to remove or 65 change the throat plate 49, without disturbing 70 75

the cloth plate, when it is desired to make repairs, changes, or adjustments to the feed dog or looper forming instrumentalities located in the lower arm 17.

Thus, the present invention provides a work 5 support 20 which is capable of a wide variety of uses, and which may be easily and quickly changed from one type of machine to another.

Preferably the walls 46, 45, 46, and 47 form a chamber 94 to house and sturdily support the 10 looper and other operating instrumentalities, with an open top and with an aperture or notch 44' in the front wall 44 to facilitate replacing and adjusting these instrumentalities.

If preferred, the work support 20 may be 15 modified slightly at the outer end of the arm 17 so that small diameter articles may be slipped in place thereon and sewed around the arm. As shown in Fig. 7 this modified structure comprises the omission of the front wall 44 between 20 the transverse end wall 46 and the intermediate transverse wall 47, with a modified end wall 46' of reduced size and preferably with a cover 94' to prevent the work from engaging the moving instrumentalities at that point. The foot 17' 25 allows this modified end to project from the bench or work table.

Loop spreader

A novel loop spreader mechanism 138 including a slide 139 is illustrated in Figs. 3, 8A, 9, 10, 13, 14, and 15 which, through pins 140 and 141, link 142, and connection 143 is operated by the upper rod 133 coordinately with the looper. This loop spreader slide 139 operates in the channel 144 on the under side of the throat plate 49 so as to properly be guided thereby, its location being in advance of the needles 93. This slide is provided with a looper thread engaging hook 145 when the machine is used for making stitch formation Federal Standard Stitch Type No. 401; or 40 more hooks 145', as shown by dot-and-dash lines in Figure 8, if the machine is arranged for making ornamental stitches, in which case the loop spreader may serve two needles, passing from one to the other, for instance as shown and described 45 in Patent No. 1,961,950 of June 5, 1934, to John P. Weis et al.

The connection 143 shown in Figs. 1, 10 and 15, comprises an arm 166 secured to the upper rod 133 carrying a ball stud 167 operating in one 50 end of the link 168. The other end of the link operates on ball stud 169 carried by an arm 170 of a bell crank 171, on a fixed shaft 172. The bell crank 171 has an upwardly projecting arm 175 to which is pivotally connected on a pin 141 55 a link 142, having a pivot pin connection 140 to a downwardly projecting lug formed as part of the loop spreader slide 139.

The spreader may be arranged with more than 60 one supplementary hook 145' to spread a plurality of looper thread loops and thus serve two, three or more needles as the case may be, for making ornamental stitches as, for example, shown in Patent No. 1,961,950 of June 5, 1934, granted to John P. Weis, et al. This arrangement of parts is simple in construction and positive in action. The throat plate 49 forms the principal guide and bearing for the slide 139 while the adaptor plate 60 upon which the throat plate is supported holds the slide 139 in channel 70 75 144 and permits endwise movement of the loop spreader under the action of its driving mechanism 143 without side or up and down play.

While a channel 144 is shown only in the throat plate 49, such a channel may, if preferred, be 75

provided in the adaptor plate 60. It should be particularly noted, as shown in Fig. 8A that the slide 139 may be provided with an extension 139' with a slot 140' forming a hook adapted to hook onto the pin 141, so that the link 142 may be dispensed with and so that the slide 139 may be tilted out of connection with the pin 141 and removed together with the throat plate and adaptor plate without removing the cloth plate.

10 *Needle guard*

In addition this novel shaped work support 20 provided by the present invention has associated therewith an advantageous needle guard 148, see Figs. 6, 7, 9, and 10, adapted to guide or support a single needle 93 near the bottom of its travel, and to prevent the needle from being twisted or bowed by heavy materials or excessive pulling on the stitched materials while down, and particularly to align and maintain in alignment a plurality of needles, thereby insuring a more positive and efficient high speed operation of the machine and insuring high quality stitch formation.

25 This needle guard mechanism as at present preferred is best illustrated in Figs. 9 and 10 particularly, and comprises a gate 149 pivotally mounted on a stud 150 threaded into the end wall 46 so that it may be moved to an inoperative position shown by dot-and-dash lines 149', but which is normally supported in the operative position shown by full lines in Fig. 9 with the outer or free end thereof riding or resting upon a long stud 151, and stopped in the operative position by engaging an end of an adjustable stud 152 threaded into the lug 54 and locked in adjusted position by a nut 153.

30 Normally the gate 149 is urged out to an inoperative position by a spring 154 so that the gate will not be half open or slightly open which would break loopers and needles when the latter are operated. By urging it to the open position, the operator can also more easily thread the loopers. The gate is locked in the operative position by a spring latch 156 engaging the rear end thereof. Preferably this latch is provided with a bevel 157 so that it need not be pushed back manually when the gate is moved from the inoperative to the operative position. The position of the needle at the lower end of its stroke relative to the guard 148 is clearly shown in Figs. 6 and 10. Multiple needles would, of course, be similarly located in any desired spaced relation lengthwise of the gate. The gate itself may be made of one piece construction and hardened to prevent wear from the needle; however, it is preferably provided with a hardened angular or like plate 158 held onto the top of the gate by two screws 159 passed through suitable enlarged apertures 160 and threaded into the gate proper so that minor adjustments and movement to compensate for wear can be made with comparative ease and so that replacements of the worn needle engaging surfaces may be easily and cheaply made. The guard 148 or the plate 158 thereon may be provided with holes 161 or notches 162 to guide needles.

35 In order to move the needle guard gate 149 to the inoperative position, it is merely necessary to push against the finger 163, Fig. 9, until the end 40 of the gate is clear. The front wall 44 is provided with a cut out 44' which enables an operator to reach in with his fingers to manipulate the gate. However, fine adjustments of the guard 148 relative to the needle 93, or adjustment of 45 multiple needles relative to the guard may be ac-

complished best by removal of the throat plate 49 and adaptor plate 60.

Additional mechanism disclosed but not claimed herein is more completely disclosed in our co-pending applications Serial No. 747,871, filed 5 October 11, 1934; Serial No. 755,372, filed November 30, 1934; and Serial No. 2,806, filed January 21, 1935 now respectively Patents No. 2,145,823, No. 2,145,825 and No. 2,145,826, granted January 31, 1939.

10 If preferred the throat plate and adaptor may be made of one piece, but for economy in manufacturing cost and for operating advantages are made separately as shown and described herein. Although not described in detail, it should 15 be understood that the present invention is equally applicable for use with multiple needles and multiple loopers.

Other variations and modifications may be made within the scope of the present invention and portions of the improvements may be used without others.

Having thus described the invention, what is claimed as new is:

1. In a sewing machine convertible from a flat 25 bed to a cylindrical type of sewing machine adapted to sew a tubular or cylindrical article, the combination of a frame; an arm extending from said frame; a removable cloth plate with an aperture, adapted to be connected to the arm; an adaptor plate locatable completely within the aperture and supportable on the arm; and a throat plate also locatable in the aperture and supportable on the adaptor, said adaptor and throat plate while supported on the arm permitting removal and interchangeability of the cloth plate to convert the machine from a flat bed to a cylindrical type of sewing machine.

2. In a sewing machine the combination of a main frame; a lower arm projecting from said frame; supports on said lower arm; a removable cloth plate on the supports of said lower arm, having a large aperture; a throat plate adapted to be located by the aperture; and an adaptor plate, located completely within said aperture, 45 on the supports, to support the throat plate relative to the top of the cloth plate.

3. In a sewing machine the combination of a main frame; a lower arm projecting from said frame; supports on said lower arm; a removable 50 cloth plate on the supports of said lower arm, having a large aperture; a throat plate adapted to be located by the aperture; an adaptor plate located completely within said aperture, on the supports, to support the throat plate relative to the top of the cloth plate; and means adapted to hold both the throat plate and adaptor to the supports and permitting removal of the cloth plate.

4. In a sewing machine the combination of a frame; a reciprocating needle in said frame; an 60 arm extending from said frame; a throat plate; a channel in the throat plate; an adaptor supported by said arm, underlying and supporting the throat plate; and a loop spreader slide, for operation on a looper thread, located and supported in the channel between the throat plate and the adaptor for travel relative to the needle.

5. In a sewing machine the combination of a frame; a reciprocating needle in said frame; an 70 arm on the frame; a loop spreader slide for operation on a looper thread; a throat plate; an adaptor, located and supported with the throat plate on the arm; and portions on said throat plate and adaptor cooperable to locate and sup- 75

port the spreader slide for movement relative to the needle.

5. In a sewing machine the combination of a frame; a reciprocating needle in said frame; an arm on the frame; a loop spreader slide for operation on a looper thread; a throat plate; an adaptor, located and supported with the throat plate on the arm; portions on said throat plate and adaptor cooperable to locate and support the 10 spreader slide for movement relative to the needle; a driving connection; and a hook on said slide adapted to hook onto the driving connection.

7. In a sewing machine the combination of a frame; an arm extending from said frame; a reciprocating needle in said frame; a relatively thick cloth plate supported by said arm and having an aperture; a relatively thin throat plate located by said aperture and indirectly supported 20 by said arm; an adaptor located by said aperture and supported by said arm for locating said thin throat plate substantially level with the top of the cloth plate; portions on said throat plate and said adaptor cooperable to form a 25 closed guide channel; a driving connection underlying said cloth plate; and a loop spreader slide, for operation on a looper thread, located and supported by said portions in the channel between the throat plate and the adaptor, and 30 having means for association with the driving connection underlying the cloth plate.

8. In a sewing machine the combination of a frame; an arm extending from said frame; a reciprocating needle in said frame; a relatively thick cloth plate supported by said arm and having an aperture; a relatively thin throat plate located by said aperture and indirectly supported by said arm; an adaptor located by said aperture and supported by said arm for locating said thin throat plate substantially level with the top of the cloth plate; portions on said throat plate and said adaptor cooperable to form an enclosed 40 guide channel; and a loop spreader, for operation on a looper thread, located and supported by said portions in the channel between the throat plate and adaptor for travel relative to the needle.

9. In a sewing machine the combination of a

frame; a movable needle in said frame; an arm on said frame; a reciprocating operating rod in said arm; a loop spreader slide for operation on a looper thread; a throat plate; an adaptor located and supported with the throat plate on the arm; portions on said throat plate and adaptor cooperable to locate and support the spreader slide for movement relative to the needle; and means connecting said operating rod to said slide for actuating the latter.

10. In a sewing machine the combination of a frame; a movable needle in said frame; an arm on said frame; a looper; a looper operating rod in said arm; a loop spreader slide for operation on a looper thread; a throat plate; an adaptor located and supported with the throat plate on the arm; portions on said throat plate and adaptor cooperable to locate and support the spreader slide for movement relative to the needle; and means connecting said rod to said slide for actuating the latter coordinately with said looper.

11. In a sewing machine the combination of a frame; a movable needle in said frame; an arm on said frame; a looper; a looper operating rod in said arm; a loop spreader slide for operation on a looper thread; a throat plate; an adaptor located and supported with the throat plate on the arm; portions on said throat plate and adaptor cooperable to locate and support the spreader slide for movement relative to the needle; a bell crank oscillatable by said rod; and means connecting said bell crank to said slide for actuating the latter in timed relation with said looper.

12. In a sewing machine the combination of a frame; an arm on said frame; an interchangeable cloth plate having an aperture; an interchangeable throat plate located by said aperture; an adaptor located completely within said aperture; and means only on the arm for locating and supporting said cloth plate, adaptor plate, and throat plate, and adapted to permit removal of the cloth plate without disturbing the throat plate and adaptor and vice versa.
